(57) **CLAIM**

The ornamental design for an overbed table, as shown and described.

DESCRIPTION

In a preferred embodiment, the nature of this product is an overbed table of the type cantilevered over a patient support, such as a hospital bed, and configured to support materials used by the patient.

FIG. 1 is a front and top perspective view of an overbed table showing our new design;

FIG. 2 is a top plan view thereof;

FIG. 3 is a front elevation thereof;

FIG. 4 is a rear elevation thereof;

FIG. 5 is a right side elevation thereof;

FIG. 6 is a left side elevation; and,

FIG. 7 is a bottom plan view thereof.

The broken line representations of cup holders in FIGS. 1, 2, and 7, of wheels in FIGS. 1, 3–7, of table adjustment structure in FIGS. 1, 3–7, and the bottom of table support structure in FIG. 7 are for the purpose of illustration only, and form no part of the claimed design.
